UNITED STATES PATENT OFFICE.

CHARLES E. GIERDING, OF NEWARK, NEW JERSEY, ASSIGNOR TO STERLING-MEAKER COMPANY, OF NEWARK, NEW JERSEY, A CORPORATION OF NEW JERSEY.

FARE-REGISTER.

No. 800,566.

Specification of Letters Patent.

Patented Sept. 26, 1905.

Application filed November 25, 1904. Serial No. 234,231.

To all whom it may concern:

Be it known that I, CHARLES E. GIERDING, a citizen of the United States of America, and a resident of Newark, in the State of New Jersey, have invented a new and useful Improvement in Fare-Registers, of which the following is a specification.

This invention relates to what are known as "double" fare-registers—that is to say, fare-registers adapted for the registration separately of cash fares and transfers or any other two kinds of fares and for the indication at all times of the kind of fare last registered.

The invention consists in certain novel combinations of parts hereinafter described and claimed. These combinations have been and are preferably embodied in an improved double register, other features of which will be claimed in companion specifications, but which will be shown as a whole and briefly described to set forth the intended and preferred setting of the present invention.

The objects of the present invention have reference to the construction and operation of the fare-indicator and are to facilitate the construction of a light but rigid indicator of as large size as a given register will accommodate, and thus adapted to carry large and conspicuous signs, to transmit motion thereto from actuation-indicators connected with the respective registering-trains, to keep the fare-indicator from being accidentally moved or displaced, and to facilitate its removal from the register and the substitution of an indicator bearing other fare indications or signs.

Three sheets of drawings accompany this specification as part thereof.

Figures 1 and 2 are respectively a face view and a side view of the aforesaid improved fare-register, together with its operating-back. Figs. 3 and 4 are face views of the operating-back detached with portions broken away in the latter to expose parts concealed in Fig. 3. Fig. 5 is a face view, on a larger scale, of the register proper with the front of the drum and the dial-plate removed. Fig. 6 is a face view of the fare-indicator detached, showing the cash-fare sign concealed in Figs. 1 and 5. Figs. 7 and 8 are edge views of the back-plate of the register proper, showing the respective sides of the mechanism attached thereto. Figs. 9 and 10 show the respective ends of the

detached fare-indicator, and Fig. 11 shows its hollow back.

Like reference numbers and letters indicate corresponding parts in the several figures.

The register proper and its operating-back are shown, respectively, at A and B in Figs. 1 to 4, inclusive.

The external characteristics of the register A include a round case, formed by sheet-metal drum parts 1 and 2, connected with each other by bayonet-joints *a* and adapted to be secured against unauthorized separation by a pair of locking or sealing lugs *a*² and *a*³, (shown, respectively, in Fig. 1 and Fig. 5,) through which the shackle of a small padlock or a seal may be passed. At the front of the case a circular dial-plate 3 is exposed to view, as in Fig. 1, through a sheet of glass. This dial-plate has seven index-openings, two of which, *b* and *b*², expose to view the numerals on the trip-register wheels *c* and *c*² and the respective actuation-indicators *d* and *d*², Fig. 5, &c; another pair, *b*³ and *b*⁴, the numerals on the respective totalizer-wheels *e* and *e*²; a third pair, *b*⁵ and *b*⁶, the respective signs of the fare-indicator *f*, and the seventh opening, *b*⁷, the respective signs of the direction-indicator *g*. All the descriptive signs are disappearing. Only those that are for the time being correct are exposed to view.

The back of the register-case is formed, as is customary, by a cast-iron back-plate 4, having hanging lugs *h* and *h*² at top and bottom, which are the only portions thereof exposed to view in Figs. 1 and 2.

The operating-back B is provided with the customary staples *i* and *i*² at top and bottom to interlock with said hanging lugs *h* and *h*² on the back-plate of the register proper. Its other characteristics are a recessed body-casting 5, with which said staples *i* and *i*² are integral or to which they are rigidly attached; a locking device, *i*³, attached to that portion of the body-casting which supports the lower staple *i*; a central fixed pivot, *i*⁴, on said body-casting; a pair of T-shaped levers, 6 and 7, fulcrumed on said pivot *i*⁴, with their central members *j* and *j*² normally vertical and adapted for rod or cord connection at either or both sides of the car; a pair of suitably-shaped bell-crank levers 8 and 9, pivoted to the body-casting 5 near its respective sides and each constructed with a slotted main arm *k*, hav-

- ing a rearwardly-projecting stud, l^2 , (shown in section in Fig. 4,) to contact with the main levers 6 and 7, and with secondary arms, l^3 , projecting in the same vertical plane as said main arms, and a single tensile spring 10, connecting said secondary arms l^3 and forming a retracting-spring for all the movable parts. Said bell-crank levers 8 and 9 are further constructed with extensions, l^4 , to cover the respective slots in the back-plate 4 of the register and with stop-lugs l^5 , which are normally in contact with the ends of lateral slots or notches, l^5 , in the sides of said body-casting 5, as shown in Fig. 4.
- 15 The resetting mechanism, (shown at 11, &c., in Figs. 5 and 7,) and the direction-indicator g are operated by an external key 12, projecting downwardly at one side of the register, as in Figs. 1 and 2 and Figs. 5 and 7.
- 20 This key is detached to open the case, but is shown in normal position in Figs. 5 and 7 by way of accommodation in view of its relation to the resetting mechanism. The slots of said slotted main arms l of the bell-crank 25 levers 8 and 9 within the operating-back B admit in customary manner rearwardly-projecting studs l and l' , Figs. 7 and 8, on the backs of vertically-reciprocating main slides 13 and 13', which are suitably guided on the face of 30 the back-plate 4. From each of these main slides 13 and 13' at each pull of an actuating handle or cord motion is simultaneously transmitted to the units-wheel of one series or the other of said trip-register numeral-wheels c and c' , the units-wheel of the corresponding series of said totalizer numeral-wheels e and e' , and the corresponding hammer, m or m' , Fig. 5, of a bell mechanism comprising a central bell, (not shown,) which attests the registration of each unit in a customary manner.
- 35 Simultaneously with each movement of the units-wheel of either series of said trip-register wheels c and c' the corresponding actuation-indicator d or d' is moved concentrically therewith and serves to conceal the numerals of the series after a registering actuation is begun until that actuation is completed, motion being transmitted to these indicators d and d' from convenient moving 40 parts of the trip-register train.
- 45 The individual numerals on the trip-register wheels c and c' and on the numeral-wheels e and e' of the totalizers are framed, or partly framed, by rectangular notches, 14, in the lower edges of said actuation-indicators d and d' and by a frame-strip, 15, attached to the front edges of the two side pieces 16 and 16', between which the registering mechanism as a whole is supported.
- 50 The fare-indicator f is common to both registering-trains of the double register and parallel with the axes of their numeral-wheels c and c' and e and e' and with said actuation-indicators d and d' and is preferably and conveniently 55 located between said actuation-indicators d

and d' and said frame-strip 15, so as to expose its signs midway between the exposed numerals of the trip-register wheels c and c' and the numeral-wheels e and e' of the totalizers, as in Figs. 1 and 5. This fare-indicator f , in which the present invention more particularly consists, is of peculiar construction and peculiarly operated as compared with known devices having the same object. The body, 17, of the fare-indicator f is formed of suitable sheet metal attached to cast-metal end pieces 18 and 18', which may preferably and conveniently be of brass. Said end pieces 18 and 18', around which the respective ends of said body 17 are soldered fast, include outwardly-projecting pivotal journals 19 and 19', supported within bearings n and n' , formed in said side pieces 16 and 16', respectively, the right-hand bearing n' being preferably and conveniently closed on all sides, as shown in Fig. 7, and the left-hand bearing n provided with a detachable cap o , as shown in Figs. 5 and 8, so as to render two or more fare-indicators interchangeable, and thus to facilitate changing the signs represented by the words "Transfers" and "Cash fares." The respective signs, whatever they may be, appropriate to the two kinds of fares are carried by the respective sides of the body 17 of the indicator, which is of the peculiar shape in 95 end view and cross-section indicated by Figs. 9 and 10 and by dotted lines in Fig. 7. The cast-metal end pieces 18 and 18' facilitate giving the body 17 that shape or any other shape in cross-section that may be preferred for the effective display of the signs alternately and at the same time to render the indicator as a whole light but rigid and free from liability to get out of shape. The outer ends of said journals 19 and 19' of the fare-indicator f are provided in common with holes 20 and 20', Figs. 9 and 10, tapped to receive crank-pins-forming screws 21 and 21'. These screws 21 and 21' are inserted through round holes in sliding pitmen p and p' , having longitudinal slots 22 and 22', through which guide-screws q and q' are inserted into the respective side pieces 16 and 16'. The upper ends of said pitmen p and p' are squared or otherwise suitably shaped to contact with stud-pins 23 and 23', projecting laterally from the oscillatory frames of the respective actuation-indicators d and d' . Provision is thus made for transmitting motion from said actuation-indicators d and d' by way of said stud-pins 23 and 23', pitmen p and p' , and crank-pins 21 and 21' to the fare-indicator f , so as to turn it on its axis to the required extent to bring into its exposed position the appropriate sign. The sign "Transfers" is shown in such position in Figs. 1 and 5.

100 To keep the fare-indicator f from being accidentally turned, so as to retain a given sign in effective position as long as fares of its description are being registered, one of said 105

110

115

120

125

130

journals 19 and 19' of the indicator is further provided with a headed crank-pin 24, diametrically opposite its other crank-pin 21, and a tensile spring *r* is stretched therefrom to a relatively fixed support *s*. In passing from one of its positions of rest to the other (shown, respectively, by full and dotted lines in Fig. 8) the crank-pin 24 must elongate the tensile spring *r*, and the tension of the latter consequently tends to hold the fare-indicator *f* in either of said positions and to resist such movement to a sufficient extent to keep the indicator from being accidentally turned or displaced. The head of the screw forming the other crank-pin 21, adjacent to said spring *r*, may project in the path of the spring, so that the spring will have to be sprung over it in passing from one position to the other, thus materially increasing the resistance of the spring to the movement of the indicator.

When an actuating handle or strap is pulled to register a fare, if the appropriate sign is not already exposed to view, as at the left in Figs. 1 and 5, the stud-pin 23, or 23', on the moving actuation-indicator, *d* or *d'*, will come in contact with the upwardly-projecting squared end of the corresponding indicator-pitman, *p* or *p'*, and will force such pitman into its lowered position, thereby turning the fare-indicator *f* on its axis against the resistance of said tensile spring *r* and its appurtenances, and thereby bringing into view the appropriate sign.

At the end of each trip or half-trip indicated by the respective signs on the direction-indicator *g* the resetting-key 12 and the tubular shaft 11, coupled thereto, are pulled lengthwise, so as to disengage a locking-pin 25 (shown in dotted lines in Fig. 7) from its socket in a relatively fixed part 26. The resetting-key 12, and therewith said tubular shaft 11 and a shaft 27 within the latter, (indicated in dotted lines in Fig. 7,) are then turned in the direction of least resistance and motion is transmitted from said inner shaft 27 through beveled gears 28 and 29 to a horizontal shaft 30 common to the numeral-wheels *c* and *c'* of both trip-registers, from which shaft motion is transmitted to the respective trip-register numeral-wheels *c* and *c'*, which are thereby turned until they are stopped at zero. The resetting movement is limited to one direction by a pawl and ratchet 31 and 32, Fig. 8. Simultaneously with the resetting operation and as a check on the latter the direction-indicator *g* is moved to indicate the next succeeding trip, its movement being effected in the following manner: When the shaft 30 is turned by the resetting-key 12, a pinion 33, Fig. 8, thereon rotates a crank-wheel 34, the wrist-pin of which is connected by a link 35 with a lever-arm 36, fast on a horizontal rock-shaft 37, to which the direction-indicator *g* is attached.

For the purposes of the present invention 65 said operating-back *B*, said main slides 13 and 13', with their appurtenances, said registering-trains, bell mechanism, resetting mechanism, and direction-indicator may be of any known or improved construction, except that the 70 present invention has been made with special reference to the adaptation of the improved fare-indicator to the other parts of the specific double register above described and shown in the accompanying drawings. 75

Having thus described said improvement, I claim as my invention and desire to patent under this specification—

1. The combination, in a fare-register, of devices for registering two kinds of fares, actuation-indicators movable with the respective registering devices, a fare-indicator common to both registering devices provided with a sign for each kind of fares, and composed of a sheet-metal body forming faces for the several signs, and cast-metal end pieces having horizontal journals integral therewith, supporting means forming bearings for the respective journals, and means for transmitting motion from each of the actuation-indicators 85 to the fare-indicator to turn said fare-indicator on its axis and thus to bring the proper sign into view and to make the other sign disappear. 90

2. The combination, in a fare-register, of devices for registering two kinds of fares, actuation-indicators movable with the respective registering devices, a fare-indicator common to both registering devices provided with a sign for each kind of fares and having horizontal journals, supporting means forming bearings for the respective journals, one of said bearings being open and provided with a removable cap to render a given fare-indicator interchangeable with another or others 100 having different signs, and means for transmitting motion from each of the actuation-indicators to the fare-indicator to turn said fare-indicator on its axis and thus to bring the proper sign into view and to make the other 105 sign disappear. 110

3. The combination, in a fare-register, of devices for registering two kinds of fares, actuation-indicators movable with the respective registering devices, a fare-indicator common 115 to both registering devices provided with a sign for each kind of fares and having horizontal journals, supporting means forming bearings for the respective journals, and means for transmitting motion from each of the actuation-indicators to the fare-indicator to turn said fare-indicator on its axis and thus to bring the proper sign into view and to make the other sign disappear, such transmitting means comprising laterally-projecting studs on the respective actuation-indicators, sliding pitmen having their upper ends adapted to contact with said studs and crank-

pin-forming screws attaching said pitmen sub-jacently to the respective journals of the fare-indicator.

4. The combination, in a fare-register, of 5 devices for registering two kinds of fares, actuation-indicators movable with the respective registering devices, a fare-indicator common to both registering devices provided with a sign for each kind of fares and having horizontal journals, supporting means forming 70 bearings for the respective journals, means for transmitting motion from each of the actuation-indicators to the fare-indicator to turn said fare-indicator on its axis and thus to bring 15 the proper sign into view and to make the other sign disappear, and means for keeping the fare-indicator from being accidentally turned or displaced, these means comprising a suitably-located crank-pin on one of said 20 journals, a tensile spring attached to this crank-pin, and a relatively fixed support to which said spring is stretched, substantially as hereinbefore specified.

5. The combination, in a fare-register, of 25 devices for registering two kinds of fares, actuation-indicators movable with the respective registering devices, a fare-indicator common to both registering devices provided with a sign for each kind of fares and having horizontal journals, supporting means forming 80 bearings for the respective journals, means for transmitting motion from each of the actuation-indicators to the fare-indicator to turn said fare-indicator on its axis and thus to bring 30 the proper sign into view and to make the other sign disappear, such transmitting means comprising laterally-projecting studs on the respective oscillatory parts, sliding pitmen having their upper ends adapted to contact with said studs, and crank-pin-forming screws attaching said pitmen sub-jacently to the respective journals of the fare-indicator, substantially as hereinbefore specified.

6. In a double-fare register, a fare-indicator composed of a hollow-backed sheet-metal body forming faces for alternately exposed and disappearing signs, and cast-metal end pieces having horizontal journals integral therewith, in combination with means for turning said indicator on the axis of said journals and means for securing it in its respective positions of rest against accidental movement, substantially as hereinbefore specified.

7. In a double-fare register, a fare-indicator composed of a hollow-backed body forming faces for alternately exposing and displaying 60 signs, and end pieces having horizontal journals integral therewith, in combination with means for turning said indicator on the axis of said journals, substantially as hereinbefore specified.

65 8. The combination, in a fare-register, of

devices for registering two kinds of fares, oscillatory parts movable with the respective registering devices, a fare-indicator common to both registering devices provided with a sign for each kind of fares and having horizontal journals, supporting means forming 70 bearings for the respective journals, one of said bearings being open and provided with a removable cap to render a given fare-indicator interchangeable with another or others 75 having different signs, and means for transmitting motion from each of said oscillatory parts to the fare-indicator to turn said fare-indicator on its axis and thus to bring the proper sign into view and to make the other sign disappear, substantially as hereinbefore specified.

9. The combination, in a fare-register, of devices for registering two kinds of fares, oscillatory parts movable with the respective 85 registering devices, a fare-indicator common to both registering devices provided with a sign for each kind of fares and having horizontal journals, supporting means forming 90 bearings for the respective journals, and means for transmitting motion from each of said oscillatory parts to the fare-indicator to turn said fare-indicator on its axis and thus to bring the proper sign into view and to make the other sign disappear, such transmitting means 95 comprising laterally-projecting studs on the respective oscillatory parts, sliding pitmen having their upper ends adapted to contact with said studs, and crank-pin-forming screws attaching said pitmen sub-jacently to the respective journals of the fare-indicator, substantially as hereinbefore specified.

10. The combination, in a fare-register, of devices for registering two kinds of fares, oscillatory parts movable with the respective 105 registering devices, a fare-indicator common to both, registering devices provided with a sign for each kind of fares and having horizontal journals, means for transmitting motion from each of said oscillatory parts to the 110 fare-indicator to turn said fare-indicator on its axis and thus to bring the proper sign into view and to make the other sign disappear, and means for keeping the fare-indicator from being accidentally turned or displaced, these 115 means comprising a suitably-located crank-pin on one of said journals, a tensile spring attached to this crank-pin and a relatively fixed support to which said spring is stretched, substantially as hereinbefore specified.

11. The combination, in a fare-register, of devices for registering two kinds of fares, oscillatory parts movable with the respective registering devices, a fare-indicator common to both, registering devices provided with a 125 sign for each kind of fares and having horizontal journals, means for transmitting motion from each of said oscillatory parts to the fare-indicator to turn said fare-indicator on its axis and thus to bring the proper sign into 130

view and to make the other sign disappear, and means for keeping the fare-indicator from being accidentally turned or displaced, these means comprising a suitably-located 5 crank-pin on one of said journals, a tensile spring attached to this crank-pin, a relatively fixed support to which said spring is stretched and a projection in the path of said spring

over which it must be sprung in changing the position of the fare-indicator, substantially as hereinbefore specified.
